UNITED STATES PATENT OFFICE.

DAVID H. NATION, OF ST. LOUIS, MISSOURI, ASSIGNOR TO THE EXCELSIOR MANUFACTURING COMPANY, OF SAME PLACE.

RANGE.

SPECIFICATION forming part of Letters Patent No. 247,777, dated October 4, 1881.

Application filed February 7, 1881. (Model.)

To all whom it may concern:

Be it known that I, DAVID H. NATION, of St. Louis, Missouri, have made a new and useful Improvement in Ranges, of which the following is a full, clear, and exact description, reference being had to the annexed drawings, making part of this specification, in which—

Figure 1 is a view in perspective, showing that portion of a range with which the improvement in question is immediately connected, a portion of the outer and inner plates being broken away to exhibit the interior construction and the damper being turned as for direct draft to the exit; and Fig. 2, a similar view, but showing the damper turned to direct the heat-currents around the oven.

The same letters denote the same parts.

The present invention is an improvement in ranges having three flues, and it is a modification of the construction patented to me June 1, 1880, and numbered 228,270. In the construction referred to a division-strip extends from the back side of the range to the opposite side thereof at a point just beyond the diving-flues. The present improvement has especial relation to this portion of the range.

A represents the improved range, having the fire-place B, the flue C, leading from the fire-place, the diving-flues D D, the side bottom flues E E, the center bottom flue, F, the ascending flue G, the flue-space H, the flue N, leading from the space H along the back side of the range to the escape N', and the oven I, all substantially as in the original construction. In place, however, of the flue-strip extending in rear of the diving-flues from the side a of the range continuously to the opposite side, a', of the range, the flue C and space H are made to be separated by the strips K K',

which are arranged beyond the diving-flues 40 D D, and a central damper, M—that is, for direct draft the damper is turned down, as in Fig. 1, and the heat-currents are then from the flue C into the flue-space H; thence into the flue N, and out at N', as indicated by the arrows. 45

To heat the oven the damper is turned up, as in Fig. 2, and the course of the heat-currents is then from the flue C, down the diving-flues D D, and through the flues E E, F, and G into the space H, and thence through the flue N to 50 the exit N', as indicated by the arrows in the last-named figure. The strips K K' may be extensions of the plates k k. The damper may be arranged either at the near or farther side of the strips K K'. 55

I am aware of and disclaim the construction shown in Letters Patent No. 235,350, granted Giles F. Filley December 14, 1880.

I claim—

1. In a range, A, the combination of the flues 60 C, H, and N, said flues C and H being partly separated by the strips K K', arranged and extended from the sides a and a', respectively, and leaving an opening at the top between the inner ends of the strips at the center of the 65 range, as described and shown.

2. In a range, A, the combination of the flues 60 C, D D, E E, F, G, H, and N, and the central damper, M, and strips K K', said strips extending, respectively, from the sides a and a', 70 and forming an opening at the center of said range to be closed by said damper, substantially as described.

DAVID H. NATION.
